UNITED STATES PATENT OFFICE.

ROBERT ZAHN, OF PLAUE, GERMANY.

TAKE-UP CONTROLLING MEANS FOR EMBROIDERING-MACHINES.

1,085,187.

Specification of Letters Patent.

Patented Jan. 27, 1914.

Application filed June 17, 1912. Serial No. 704,104.

To all whom it may concern:

Be it known that I, ROBERT ZAHN, a subject of the German Emperor, residing at Plauen, Kingdom of Saxony, Germany, 5 have invented certain new and useful Improvements in Take-Up Controlling Means for Embroidering-Machines, of which the following is a specification.

The present invention relates to embroidery machines having apparatus for making button hole edge stitches, known as festoon apparatus, and more particularly, to means for imparting positive motion to the take up levers.

15 In embroidering machines with festoon apparatus, the take up motion for festooning differs from that of ordinary embroidery. It is well known that hitherto when the mechanism for operating the take up 20 levers comprises separate cams and levers, it has been impossible to change from festooning to ordinary embroidery and vice versa without removing the corresponding levers from their respective cams.

25 It is the object of the present invention to provide an apparatus whereby the change from festooning to ordinary embroidery and vice versa can be effected while the engagement of the levers with the cams is 30 constantly maintained.

35 My invention is diagrammatically illustrated in the accompanying drawing in which similar reference characters denote corresponding parts and in which the figure is an elevation of the apparatus.

In the example illustrated the cams 2, 6 consist of disks having cam shaped grooves.

40 1 denotes the main shaft of the machine to which the cam 2 for ordinary embroidery is fixed. This cam constantly engages the roller 3 of a bell crank lever 4 pivotally connected to the lower end of a rod 9.

45 5 denotes the shaft on which the cam 6 for festooning is fixed. Constantly engaged in this cam is the roller 7 of a bell crank lever 8 pivotally connected to the lower end of a rod 10.

50 A reciprocating rod 15 is pivotally connected at its ends to the take up levers t , t' , and at a suitable point is provided with a coupling 13. The upper ends of the rods 9 and 10 may be formed with suitable means capable to readily engage and disengage 55 from the said coupling. In the present embodiment of my invention the coupling consists of a member 13 formed integral with

the rod 15 and which is bifurcated at both sides, as at 13¹, 13² and head pieces 11 and 12 formed on the upper ends of the rods 9 and 10, the bifurcated parts 13¹, 13² being 60 adapted to receive the heads 11 and 12 respectively, of the rods 9 and 10, so as to couple the said rods 9 and 10 to said rod 15. The rods 9 and 10 constantly engage fork shaped projections, 16, 17 provided on a 65 transversely slideable bar 18, by the displacement of which in one direction one of the rods 9 and 10 becomes coupled to and the other uncoupled from the rod 15 and by the displacement in the other direction the 70 reverse takes place.

In the position shown, the take up levers t , t' are adjusted for ordinary embroidery. When it is desired to change from this operation to festooning, the bar 18 is moved 75 to the right whereby the rod 9 becomes uncoupled from and the rod 10 coupled to the rod 15, while the roller carrying levers 4 and 8 constantly remain in engagement with their respective cams 2 and 6. 80

What I claim and desire to secure by Letters Patent is:

1. In embroidering machines, the combination with the take up members, of a cam for operating the said members for ordinary 85 embroidery, a cam for operating the same for festooning, levers positively acted upon by said cams and means for alternately connecting said levers to the said take up members without disengaging them from 90 their respective cams.

2. In embroidering machines, the combination with the take up members, of a cam for operating the said members for ordinary embroidery, a cam for operating the same 95 for festooning, levers positively acted upon by said cams, a coupling means interposed between said members and means for alternately connecting the said levers with the said coupling means without disengaging 100 them from their respective cams.

3. In embroidering machines, the combination with the take up members, of a cam for operating the said take up members for ordinary embroidery, a cam for operating 105 the same for festooning, levers positively acted upon by said cams, a rod connecting said members including a coupling member and means for alternately connecting the said levers to the said coupling member 110 without disengaging the same from their respective cams.

4. In embroidering machines, the combination with the take up members, of a cam for operating the said take up members for ordinary embroidering, a cam for operating the same for festooning, levers positively acted upon by said cams, rocking members carried by said levers and means for alternately connecting the said rocking members and the said levers to the said take up members without disengaging the said levers from their respective cams.

5. In embroidering machines, the combination with the take up members, of a cam for operating the said take up members for ordinary embroidering, a cam for operating

the said take up members for festooning, levers positively acted upon by said cams, rocking members carried by said levers, a coupling member interposed between said take up members and means for alternately 20 connecting the rocking members and said levers to said coupling member without disengaging the said levers from their respective cams.

In testimony whereof I affix my signature 25 in presence of two witnesses.

ROBERT ZAHN.
